UNITED STATES PATENT AND TRADEMARK OFFICE
Certificate

Patent No. D 455,588 S

Patented: April 16, 2002

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Horng-Yih Chou, Tai Chung, Taiwan.

Signed and Sealed this Seventh Day of October 2003.

ALAN P. DOUGLAS
Supervisory Patent Examiner
Art Unit 2911
